METHOD OF FORMING SOCKETS

Gerrit D. Hill and Augustus C. Brown, 3d, Rochester, N. Y., assignors to Sargent & Greenleaf, Inc., Rochester, N. Y., a corporation of New York

Application October 27, 1931. Serial No. 571,418

9 Claims. (Cl. 29—148.2)

The present invention relates to sockets and to the method of making the same and has for its object to provide more particularly improvements in sockets for receiving the lower ends of furniture legs, the sockets being also designed to receive any preferred or well known form of floor pad, which can be easily applied and removed when desired.

A further object of the invention is to provide an improved method of constructing sockets of this class by which they can be manufactured at a relatively low cost ready to be attached and secured when desired.

A further object of the invention is to provide an improved method of constructing sockets from substantially round or cylindrical tubing, from which sections of the desired length are cut and shaped according to different requirements and to which are applied suitable devices preferably located interiorly of the sockets for connecting them to the legs of tables, desks, and other articles of furniture, or to other parts with which sockets of this class may be found serviceable.

A further object of the invention is to provide an improved socket arranged to receive at one end the lower extremity of the leg of a table or other article of furniture and at the other end a floor engaging pad, with an element inserted within the socket and secured therein to afford means for connecting the socket with said leg.

To these and other ends the invention resides in certain improvements and combinations of parts, all as will be hereinafter more fully described, the novel features being pointed out in the claims at the end of the specification.

In the drawings:

Fig. 1 is a sectional elevation of a socket constructed in accordance with the invention;

Fig. 2 is a sectional elevation of a cylindrical section of tubing from which the socket is to be constructed;

Fig. 3 is a view in elevation showing the tubing section in position to be forced downwardly upon a former for reshaping the section;

Fig. 4 is an elevation similar to Fig. 3, but viewed from a different angle and showing the driving ram moved to position to engage the tubular section prior to forcing it downwardly upon the former;

Fig. 5 is a fragmentary plan view of the forming device as it appears before inserting the tubular section thereon;

Fig. 6 is a top plan view of Fig. 3;

Fig. 7 is a fragmentary plan showing the tu-

bular section as it appears after being shaped by the forming device shown in Fig. 3 and before the finishing dies are moved to operating position;

Fig. 8 is a similar view with the finishing dies moved to final position;

Fig. 9 is a horizontal fragmentary section drawn to an enlarged scale to show the approximate shape assumed by the tubular section when pressed downwardly by the ram upon the forming device;

Fig. 10 is a similar view showing the result of moving the finishing dies into operating position;

Fig. 11 is a sectional elevation showing the ram and finishing dies in final operating position;

Fig. 12 is a sectional elevation showing the squared tubular section with the dished anchor plate in position to be flattened by the overhead plunger to force the edges of the plate within the groove of the section, and

Fig. 13 is a similar elevation with the plunger moved to its lowest position.

Similar reference numerals throughout the several views indicate the same parts.

In the present invention the socket shown and described is particularly adapted for use on the lower ends of furniture legs as supporting shoes for the same and is also adapted for receiving the usual or any preferred type of floor pad. It will be understood, however, that sockets constructed in accordance with the present method may be used for other purposes such for example as a joint forming means between two parts to be connected or associated one with another.

Generally in the construction of the present socket, cylindrical tubing is employed which is cut off in sections or lengths corresponding to the length of the sockets, a ledge or shoulder being preferably formed on the inner wall of the tubing in advance of each severing operation. The operations of forming the ledges and of severing the sections may be carried out, for example, by the use of an automatic screw machine or by other suitable mechanism if desired. Preferably the ledge is formed by cutting an annular groove within the wall of the socket slightly in advance of the severing operation. These preliminary

steps in the construction of the socket can be rapidly performed by an automatic screw machine, as stated, but it will be understood that other methods may be employed both in the

forming of the ledges or shoulders on the inner

walls of the sections and of severing the sections from various lengths of tubing.

The present method embodies generally the grooving and severing of the sections from tubing, such as cylindrical tubing, the tapering and shaping of the sections to correspond to the shape of the furniture legs, the insertion within the sockets of the parts for connecting them with the furniture legs and the operation upon said parts within the sockets to secure them upon the walls thereof, as for example, by forcing the extremities of said parts within grooves formed interiorly of the socket or anchoring them upon ledges or shoulders on the inner face of the socket.

Referring to the drawings, one of the severed tubular sections is designated at 10a in Fig. 2 and has formed therein between its opposite ends a groove 11 by which an annular ledge or shoulder 12 is afforded for engagement with the peripheral edge portion 13 of a plate or other suitable member 14, said peripheral edge portion being received within the groove as shown in Fig. 13 and forced therein in a manner described hereinafter. The socket 10 shown in Fig. 1 embodies one example of a completed article constructed in accordance with the present method, the socket having an upper pocket 15 for receiving the lower end of one leg of a table or other article of furniture with which the socket is to be connected, preferably by a screw or nail, not shown, which is extended upwardly into the leg through a hole 16 formed in the plate member 14.

Below the plate member the pocket 17 of the socket is provided for the reception of a floor pad, not shown, of any suitable or well known design, or for other parts depending on the particular usages to which the socket may be put.

The present socket is constructed from relatively long lengths of cylindrical tubing preferably fed through a suitable machine, such for example as an automatic screw machine, and in the advancing end of the tubing the annular grooves 11 are cut in the successive sections to be severed, each of which is severed from the tubing immediately following the cutting of the groove therein. By this method large numbers of the socket sections shown in Figs. 2, 3, and 4 can be quickly produced ready to be formed either into squared sockets, or into other shapes having a greater number of sides than the squared sockets. In the squaring of the sections, a tapered former 18 is provided on a suitable base 19, the taper corresponding substantially to that of the furniture legs to which the sockets are to be attached. The former is made slightly longer than the socket section and the corners at the top of the former are beveled as indicated at 20 to permit the end of the section to be inserted thereon in advance of the reshaping operation, as shown in Figs. 3 and 6. When this has been done the ram 21 connected with any suitable operating means, not shown, is lowered to move the section downwardly to final position upon the former as indicated in Fig. 11. Upon completion of this operation the side walls of the socket will have assumed substantially the shape shown in Fig. 7, in which the corners 23 are forced outwardly into spaced relation with respect to the former, as also indicated in Fig. 9, drawn to an enlarged scale. The next step in the operation is to advance the opposing dies 24 on the base 19 until their faces 25 are brought into position to engage and shape the corners 23 of the section to correspond to those of the former 18, as

shown in Figs. 8 and 10, the operation of converting the round or cylindrical section 10a to the squared section 10 being thus completed. The dies are then withdrawn and the squared section removed from the former. The dies are held in proper alignment on the base 19 by the guides 26 thereon and are moved to and from operating position by any suitable means, not shown. It will be understood that the movement of the dies to operating position takes place immediately following the movement of the ram 21 to the position shown at Fig. 11 and that the dies serve to complete the squaring of the section under pressure sufficient to afford a proper set to the metal so that the socket will hold its shape when removed from the former.

The plate member 14 for connecting the socket with the leg or other part to be inserted within the pocket 15 is cut from suitable stock and is then dished or bowed by suitable forming means, not shown, whereby to shorten the distances between its opposite edges in order that it may be moved within the socket to a position opposite the groove 11, as shown in Fig. 12. In this position it is supported by a block or anvil 27 on a base 28 upon which the socket rests. A plunger or ram 29 is then moved by suitable means, not shown, into position to engage and flatten the plate member whereby to force its opposite edges within the groove 11 of the socket, as shown in Fig. 13, the socket being thus completed with its upper and lower pockets 15 and 17 for receiving respectively the leg of a table or other article of furniture and a floor pad, not shown.

When the socket is applied to the leg it is secured thereon by a screw not shown, extending within the leg through the opening 16 of the plate member 14, the edges of the latter being anchored upon the ledge 12 forming the upper side of the groove 11 in which said edges are disposed.

The grooves can be formed within the sections in advance of the severing operations with comparatively little extra expense and afford recesses into which the edges of the plate members can be anchored merely by reshaping the plates within the sockets or flattening the same as described. While the dishing of the plate and the flattening of the same within the socket constitutes a desirable method of forming the dividing wall between the upper and lower ends of the socket for the purpose stated, it will be understood that anchor plates for the sockets can readily be formed and applied otherwise than by the dishing and flattening method, since the desired result may be accomplished by adjusting, reshaping, or otherwise operating upon a suitable anchoring device within the socket to cause it to engage and be supported by the walls of the socket.

Where the furniture legs are round at their lower ends instead of rectangular, the cylindrical socket section shown in Fig. 2 can be given the required taper, by forcing it down upon a correspondingly tapered forming tool as by means of a ram or plunger. Subsequently a dished plate may be inserted within said section and flattened to force its peripheral edge portions within the groove thus completing the socket ready for connection to the leg of a table or other article of furniture by a screw extending upwardly through the plate into the leg.

The sections can, of course, be severed from relatively long lengths of squared tubing, but this method is more expensive than squaring the

short severed sections of round tubing and it is therefore preferred to groove and sever the sections from cylindrical tubing as described.

We claim:

5. 1. The method of forming a socket from a tubular section, comprising forming an interiorly disposed groove in the wall of the section, tapering the section, subsequently squaring the section, positioning an element within the section having oppositely disposed edge portions and operating upon said element within the section to force said edge portions within the groove.

10. 2. The method of forming sockets from cylindrical tubing, comprising forming a ledge interiorly of the tubing on the wall thereof, severing a section from the tubing having the ledge formed thereon, shaping the section to provide a socket having a plurality of angularly disposed side walls, inserting a plate member within the 15 socket and reshaping it therein to anchor it upon said ledge.

15. 3. The method of forming sockets for furniture legs, comprising forming an interiorly disposed groove in the wall of a tubular section, 20 tapering the section and reshaping the same to provide a socket having a plurality of angularly disposed sides, inserting an element within the socket for connecting it with said leg, and applying pressure to said element to force portions 25 thereof within said groove.

20. 4. The method of forming sockets from cylindrical tubing, comprising forming a ledge interiorly of the tubing on the wall thereof, severing a section from the tubing having the ledge 25 formed thereon, shaping the section to provide a socket having a plurality of angularly disposed side walls, inserting a member within the socket to form a transversely extending wall between its ends, and operating upon said member to force 30 opposite edge portions thereof in position to be engaged and held by the ledge.

35. 5. The method of forming sockets for furniture legs from cylindrical tubing, comprising forming an annular groove in the wall of the tubing, severing a section from the tubing, shaping the section to provide a socket having a plurality of angularly disposed side walls, shaping a plate member to shorten the distance between two or more of its opposing edges, inserting the 40 plate member within the socket, and applying

pressure to the plate member to increase the distance between said edge portions whereby to force them within the groove formed in said side walls.

6. The method of forming sockets from lengths of cylindrical tubing, comprising successively grooving and cutting sections from the tubing containing the grooves, forming the sections to provide angularly disposed side walls thereon, applying dish-shaped plates within the sections, and flattening the plates within the sections to force their edges within the grooves.

10. 7. The method of forming sockets for furniture legs from sections of cylindrical tubing having interiorly formed grooves, comprising tapering the section by moving it longitudinally upon a tapered anvil having angularly disposed sides, subsequently shaping the section upon the anvil to correspond to the shape of the latter, and placing a dish-shaped plate member within the section and applying pressure to the plate member to force its edges into the groove of the section.

15. 8. The method of forming sockets for furniture legs comprising interiorly grooving and cutting sections from cylindrical tubing, tapering the section by moving it longitudinally upon a tapered anvil having angularly disposed sides, shaping the section upon the anvil by moving dies in contact with the outer walls of the section and forcing said walls inwardly upon the 105 walls of the anvil, subsequently placing a plate member within the reshaped section, and deforming it within the section to force its edges within the groove of the section.

20. 9. The method of forming sockets for furniture legs from cylindrical sections of tubing, comprising forcing the cylindrical section longitudinally upon the exterior surface of an anvil having angularly disposed sides, subsequently shaping the section upon the anvil by moving 110 dies in contact with the outer walls of the section and forcing said walls inwardly upon the walls of the anvil, subsequently inserting a dish-shaped plate member within the reshaped section and expanding it therein to urge its edges 115 into contact with the walls of the section whereby to anchor the plate member within the section.
